US00D595979S

(12) **United States Design Patent**
Schweikarth et al.

(10) **Patent No.:** **US D595,979 S**
(45) **Date of Patent:** **** Jul. 14, 2009**

(54) **TABLE**

(75) Inventors: **Derek Schweikarth**, Celestine, IN (US);
Josh Butcher, Washington, IN (US);
Meghan Smith, Jasper, IN (US); **Gary**
Meredith, Sr., Dale, IN (US)

(73) Assignee: **Kimball International, Inc.**, Jasper, IN
(US)

(**) Term: **14 Years**

(21) Appl. No.: **29/319,263**

(22) Filed: **Jun. 6, 2008**

(51) **LOC (9) Cl.** **06-03**

(52) **U.S. Cl.** **D6/484**

(58) **Field of Classification Search** D6/480-489,

D6/495-499, 429-430, 477, 479, 349, 436;
108/153.1, 155, 156, 161, 50.01, 50.02; 248/188,
248/188.1, 188.8

See application file for complete search history.
